INVENTOR.
CARL STENBOL.

BY *Setherstonhaugh & Co.*
ATT'YS.

UNITED STATES PATENT OFFICE.

CARL STENBOL, OF SAULT STE. MARIE, ONTARIO, CANADA.

ROAD CONSTRUCTION.

Application filed November 21, 1927. Serial No. 234,825.

This invention relates to improvements in road construction and more particularly to improvements in roads and highways to provide a permanent wearing surface for the wheels of vehicles and to definitely regulate traffic so as to assure the greatest possible comfort and safety for the driver.

In existing construction of roads and highways it has been found that gravel or crushed stone will not make a permanent road surface without bonding with cement, asphalt, tar, or the like in view of the increased and continuous automobile traffic. The surface of the present or permanent highway extends over the entire width of the roadbed whereas the wheel contact on the surface is comparatively restricted and runs in definite lines or bands. Consequently if these lines or bands are formed with a permanent wearing surface traffic will be definitely regulated, being automatically confined to these bands or permanent wheel engaging surfaces.

The novel features of the present invention consist in providing metallic wheel strips or bands longitudinally of the roadbed and sufficiently countersunk therein to have the top flush with the surface of the road, the strips or bands being spaced to correspond with the gauge of vehicle wheels.

The composition of the metal of which these bands are formed may be such as to give strength, flexibility and to withstand wear from corrosion and abrasion. A high carbon steel such as is used for railway rails may be preferably used from an economical point of view.

Referring now to the drawings in which like characters of reference indicate corresponding parts in each figure,

Figure 1 is a perspective view of a section of roadway fitted with my improved metallic bands or strips.

Figure 2 is a section on the line 2—2 of Figure 1 showing the bands sunk in the roadbed.

Figure 3 is a sectional detail through one of the strips.

Figure 4 is a plan view of the roughened or corrugated surface of a strip.

Figure 5 is a plan view of the strip at a danger point such as a railway crossing.

Figure 6 is an enlarged section on the line 6—6 of Figure 5.

Figure 7 shows a single track road at a

danger point such as curves, around rocks or buildings or over hills.

Figure 8 shows a section of a road for heavy traffic with four tracks.

Figure 9 is a detail of the sections or strips laid around curves and formed in short sections.

Figure 10 shows the wearing strips laid around a curve of longer sections than those in Figure 9.

Figure 11 is a section of the joint plate on line 11—11 of Figure 3.

Referring now more particularly to the drawings A indicates a section of a road or permanent highway of well known construction in which are laid the metallic tracks or strips 10 and 11 formed with their top surface roughened or corrugated in any well known manner as at 12 (see Figure 4). These track members are countersunk in the roadbed so that the roughened surface 12 will be flush with the surface 13 of the road, the dimensions being determined by the traffic that is to be carried.

The under side of these track members is curved as at 14 so as to allow the band being thicker in the centre than towards the edges. It is also provided with a rib or ribs 15 running longitudinally on the under side. These bands or tracks 10 and 11 will be manufactured in suitable lengths for shipment and handling and laid together in the roadbed as at 16, the joints being made with plates or bolts, as hereinafter more fully described.

Two of these track members form one track and are held to gauge by suitable tie bars 17 buried in the roadbed 18. Joint plates 20 on the under side of the sections will hold the whole track in alignment with the road.

Referring more particularly to Figure 1, the track members 10 and 11 are formed in two sections joined together by means of a joint plate 20 and tie bar 17 sunk in the roadbed. As the track members 10 and 11 are to some extent vertically flexible any heaving or settling of the roadbed will not cause much inconvenience.

It will be noted that the plate 20 may be folded (see Figure 3) as at 21 into the depression or recess 22 formed in the track member 10 or 11. The rib 15 is formed with a rolled wearing plate and runs longitudinally the full length of the track, its purpose

being to reinforce the track without adding an excess of material and also to form an anchor in the roadbed to hold the track to gauge and to the line of the road.

5 The member 20 is preferably, as illustrated, bolted or riveted to the tie bar 17.

In Figure 5 are disclosed track members laid at the approach to a railroad crossing 23 or other danger points where the driver 10 is required for his own safety to "stop, look, and listen." In this construction the track members are provided, in addition to the roughened surface, with ribs 24 integral therewith (see Figure 6) to more effectively 15 engage with the wheels of the vehicle and to set up a noticeable vibration thereby warning drivers automatically of approaching danger. These ribs 24 may be formed in and part of track sections 10 and 11 or 20 made separately and bolted or riveted to the upper surface of the track sections 10 and 11.

Figure 7 shows a single track road at dangerous points such as curves, around 25 rocks or buildings or over hills where the driver has a very limited view of approaching vehicles. The single track is laid to the right from both sides of the danger point and carried on for sufficient length until 30 the danger is passed.

Figure 8 discloses a method of laying the tracks for very heavy traffic including four tracks on which a slow driver on the right hand centre track would have to turn onto 35 the curb or slow track to allow the faster driver to pass providing the greatest comfort and safety.

Figures 9 and 10 show a modified form of 40 laying the track in a plurality of sections 25 for curves.

An alternative to the joint illustrated in Figs. 3 may be made by simply bolting or riveting the joint plate 20 to track sections 10 and 11 omitting recess 22.

45 As many changes could be made in the above construction and many apparently widely different embodiments of my invention within the scope of the claims, constructed without departing from the spirit

or scope thereof, it is intended that all matter contained in the accompanying specification and drawings shall be interpreted as 50 illustrative and not in a limiting sense.

What I claim as my invention is:—

1. Road construction including spaced longitudinally extending rails formed in sections countersunk in the roadway, said rails being provided on the underside with a continuous reinforcing rib, joint plate means for clamping the sections together, 60 and retaining means in the form of a tie bar rigidly connected to the afore-mentioned means.

2. The invention according to claim 1 in which recesses are formed in the rail sections for engagement with the joint plate.

3. The invention according to claim 1 in which the outer ends of the joint plate are folded to engage with and clamp the rail sections.

4. The invention according to claim 1 characterized by the fact that joint plates are provided for the rails and recesses formed in the rails to engage with the folded ends of the joint plates.

5. A roadway having a pair of spaced parallel longitudinally extending rails disposed therein and flush with the top surface thereof, a roughened tread surface for said rails, side recesses at spaced points in the rails, joint plates sunk in the roadbed adapted to engage with said recesses, and transversely extending means rigidly secured to 80 said joint plates.

6. In road construction and in combination with the roadway, rail sections formed with a continuous reinforcing rib countersunk in the roadway, joint plates for said sections comprising a flat base portion with extensions at each end to engage with and 90 clamp a rail, a transversely extending tie bar in the roadbed, means for rigidly securing the joint plates to said bar, and spaced cross-ribs for the rail sections adapted to effect vibration.

In witness whereof I have hereunto set my hand.

CARL STENBOI.
